UNITED STATES PATENT OFFICE.

EDWARD O. HOUSE, OF TROY, NEW YORK.

DESIGN FOR A COLLAR OR CUFF.

SPECIFICATION forming part of Design No. 18,983, dated April 2, 1889.

Application filed February 5, 1889. Serial No. 298,772. Term of patent 3½ years.

To all whom it may concern:

Be it known that I, EDWARD O. HOUSE, a citizen of the United States, residing at Troy, in the county of Rensselaer and State of New York, have invented and produced a new and original Design for an Apparel Collar and Cuff for Ladies' Wear, of which the following is a specification, reference being had to the accompanying Drawings, forming a part hereof.

10 Figure 1 shows a plan view of the collar. Fig. 2 shows a perspective view of the same. Fig. 3 shows a perspective view of a cuff. Fig. 4 is a sectional view on lines *y y* of Fig. 1.

15 The leading feature of my design consists of a row or series of projections along the upper edge of a lady's collar or cuff and extending outwardly therefrom, said projections being triangular in form, with the base of said triangle along the upper edge of the collar or

20 cuff.

The letter A designates the collar or cuff proper, which may be of shapes shown in Figs. 1 and 3, or have rounded corners, as shown by dotted lines X in Fig. 1, or slanting corners, as shown by dotted lines Z in Fig. 1, or opened or spaced front V, as shown in Fig. 2, or of other ordinary form, without changing my design.

The letter B designates a cape such as is usually attached to a lady's collar, but which 30 forms no part of my invention.

The letters C C designate the row or series of projections arranged along the upper edge of the collar or cuff proper, A, and extending outwardly, as shown.

Having thus described my design for an apparel collar or cuff for ladies' wear, what I claim, and desire to secure by Letters Patent, is—

The design for a collar or cuff herein shown 40 and described, the same consisting of the collar or cuff proper, A, and the row or series of projections C along the upper edge of said part A and extending outwardly therefrom, said projections being triangular in form, with 45 the bases thereof along the upper edge of said collar or cuff proper.

In testimony whereof I have hereunto set my hand this 2d day of February, 1889.

E. O. HOUSE.
